(57) **CLAIM**

We claim the ornamental design for a book/magazine vending machine, as shown and described.

DESCRIPTION

FIG. 1 is a perspective view of a book/magazine vending machine showing our new design;

FIG. 2 is a front elevational view thereof;

FIG. 3 is a rear elevational view thereof;

FIG. 4 is a right side elevational view thereof, the left side elevational view being a mirror image thereof; and,

FIG. 5 is a top plan view thereof, the bottom plan view being identical thereto.
